(57) **CLAIM**

The ornamental design for a C-TINE, as shown and described.

DESCRIPTION

FIG. 1 is a top and side perspective view of a C-TINE showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in FIGS. 1-7 are for illustrative purposes only and form no part of the claimed design.

The C-TINE is of a type that is suitable for use with a cultivator.
